UNITED STATES PATENT OFFICE.

WILFRED QUINTAL, OF HARTFORD, CONNECTICUT.

COMBINED HONE AND STROP.

Application filed February 3, 1922. Serial No. 533,744.

To all whom it may concern:

Be it known that I, WILFRED QUINTAL, a citizen of the United States of America, residing at Hartford, in the county of Hartford and State of Connecticut, have invented 5 certain new and useful Improvements in a Combined Hone and Strop, of which the following is a specification.

This invention relates to improvements 10 in razor hones and stropping devices.

An object of the invention is to combine 15 into a single structure a hone and strop device that is secured to a rigid backing or support, and of such dimensions as to make it convenient to carry in the pocket, if desired, as it is often necessary for barbers to visit their customers.

A further object of the device is to treat 20 one section of a strip of leather to form a honing surface, the other section being designed for use as a strop, so that both the honing and stropping operations may be performed on one strip of leather or other suitable material.

25 A further object of the invention is to provide means for securing the strip of leather to the backing piece, as will be fully described.

Referring to the drawings:

30 Fig. 1 is a side elevational view showing a portion of the backing member, the strip of leather, and the means for securing the leather to the backing.

35 Fig. 2 is a plan view of Fig. 1 illustrating the hone and strop portions.

Fig. 3 is a longitudinal sectional view on the line 3—3 of Fig. 2 and Fig. 4 is a modification showing the hone and strop secured to the wooden backing piece.

40 Referring to the drawings in detail: 1 designates the backing or base piece to which the strip of leather that forms the hone and strop portions is secured. The hone or treated portion is indicated at 2 and

45 the strop portion at 3. The part 2 is treated with some substance, compound, or mechanical mixture that readily enters the pores of the leather or other material as finely ground or pulverized carborundum and oil which becomes intimately incorporated therewith. The preparation that is used to treat this part of the leather, however, forms no part of the present invention. The portion of leather indicated at 3

50 has the usual stropping or finishing surface and is only treated with oil.

The strip of leather is secured to the backing 1 by means of strips 4 of thin material, as tin or aluminum. These are secured to the edge of the base 1 by the screws 5 or any suitable means. Formed integral 60 with the strips 4 are the cross pieces 6 which extend over the upper surface of the strip of leather and down on the opposite edge, where they are connected with the oppositely located strip 7, which is secured to the opposite edge of the base 1 as indicated at 8.

It will be seen from this description that I have provided a combined hone and strop apparatus that is simple and inexpensive in 70 construction and one that can be readily carried by the user.

It is of course obvious that the strip of leather 3 and the hone part 2 may be secured to the wooden backing 1 by gluing 75 as readily understood, and as shown in Fig. 4.

It has been found from experience that when a razor is honed and stropped as indicated in Fig. 2 by moving the edge of the 80 razor blade diagonally or transversely across the hone surface 3, and the stropping surface 2, as shown by the arrows that the edge of the blade is formed with small serrations that are somewhat curved on one edge that is to say instead of the serrations being triangular in shape they have one edge that is curved. This form of edge has been verified under the microscope. The result of this is that the blade is formed 85 with an edge that renders shaving very much easier and comfortable.

Fig. 2 shows a razor being honed and stropped by using the guard thereon which guard is shown, described and claimed in 95 my companion application Serial Number 533,745, dated Feb. 3, 1922 filed even date herewith to which reference may be made for a full description and use.

What I claim is:

In a device of the kind described comprising the combination with a rigid base member, a strip of leather like material, secured thereto, securing means for attaching the same to the said member and comprising oppositely located strips designed to be attached to the oppositely located edges of the base, and transverse strips connected to the side strips and extending across the upper surface of the strip of leather, substantially as shown and described.

WILFRED QUINTAL.
